UNITED STATES PATENT OFFICE.

JACOB KLAR, OF RODNEY, MISSISSIPPI.

DESK.

SPECIFICATION forming part of Letters Patent No. 297,940, dated April 29, 1884.

Application filed October 10, 1883. (Model.)

To all whom it may concern:

Be it known that I, JACOB KLAR, of Rodney, Jefferson county, Mississippi, have invented a new and Improved Adjustable Desk, 5 of which the following is a full, clear, and exact description.

My invention consists of a simple contrivance of the supporting-frame of a desk, table, bench, case, or other similar article, for adjusting the same vertically to suit the requirements of persons of different heights, and for sitting or standing at the desk or table, all as hereinafter fully described.

Reference is to be had to the accompanying 15 drawings, forming part of this specification, in which similar letters of reference indicate corresponding parts in all the figures.

Figure 1 is an end elevation of a vertically-adjustable desk, with top broken off, arranged 20 in accordance with my invention, and being elevated for use by a person standing. Fig. 2 is an end elevation of the same adjusted for a sitting person. Fig. 3 is partly a front elevation and partly a sectional elevation, and 25 Fig. 4 is a detail in plan view.

The permanent bench consists of the legs *a*, cross-bars *b*, and connecting-rod *c*, which may be made in any approved form, and constructed 30 of suitable height to support the desk or table top *d* sufficiently low down for use by a person sitting in a chair.

On the center of the cross-bar *b* of each end of the frame I fix an upright standard, *e*, having a slot, *f*, extending nearly the whole 35 length, and also having a toothed bar, *g*, attached to one side and ranging along the slot. These standards *e* rise about as high as the table or desk top is to be elevated, and extend through vertical openings of the same, for 40 guides and supports to the said top in shifting up and down.

To the top of each post *a*, I pivot a curved arm, *h*, making a pair of said arms for each end of the table or desk, which overlap each 45 other, and the said arms have a curved slot, *i*. The shaft *j* passes through all of said slots, said shaft extending from end to end of the desk or table, and also passing through the slots *f* of the vertical supports *e*, and gearing 50 at each end by a toothed pinion, *k*, with the toothed racks *g* on the standards *e*, so that with a crank applied to one end of the shaft the

desk or table top may be raised or lowered, according as the shaft is turned one way or the other, and the pinions are made to run up or 55 down the toothed racks, thereby carrying and swinging the curved arms *h*, on which the desk-top rests. A hook-pawl, *l*, is pivoted to the desk-top to drop into the notches of one of the pinions *k*, to hold the desk at any desired 60 height. The pawl is to be raised out of the notches by hand when the desk is to be shifted. When the desk is raised to the highest position, the top extends a little above the top of the standards *e*, so that it is desirable to cover the 65 openings in the top for said standards in case the desk is to be used much in that position, for which I have provided the hinged covers *m* in suitable arrangement to swing over and close said openings. Said covers *m* may hang 70 by the hinges, as shown in Fig. 3, when the desk-top is lowered, and the standards extend up through the openings. The arms *h* are connected across the bench from end to end by stay-rods *n*, said rods connecting the pivoted 75 ends of the two arms of the respective sides of the bench, so that the arms are more substantially fixed and the action of the arms is more uniform than it would be if not thus connected.

An important advantage of my improved desk constructed as above described is the facility with which the parts may be disconnected for packing away in small space, and for transportation, and the ease of assembling 85 them again in operative connection.

Having thus described my invention, I claim as new and desire to secure by Letters Patent—

1. The combination of the curved, slotted, and jointed arms *h*, shaft *j*, and pinions *k* with 90 the desk or table supporting bench, the top *d*, and the vertical slotted standard *e*, having toothed racks *g*, substantially as described.

2. The bench consisting of legs *a*, cross-bars *b*, and connecting-rod *c*, and having the curved 95 slotted arms *h* pivoted to it, and the vertical slotted standards *e* attached to the cross-bars, in combination with the desk or table top *d*, and means, substantially as described, for shifting it and supporting it thereon at any desired height, as set forth.

3. The combination, with the supporting bench provided with standards *e*, of the table or desk top *d*, provided with vertical open-

ings at each end, extending through the same, and forming guides for the said standards, and the covers *m*, hinged to the upper surface of said top, substantially as herein shown and 5 described, whereby the openings may be closed when the desk is raised to its highest position, as set forth.

4. The slotted curved pivoted arms *h*, the

posts *a*, and the stay-rod *n*, in combination with the slotted standards *e*, desk-top *d*, shaft *io* *j*, pinions *k*, and the toothed bars *g*, substantially as described.

JACOB KLAR.
